(57) **CLAIM**

The ornamental design for a nozzle for fluid distribution, as shown and described.

DESCRIPTION

FIG. 1 is a perspective view of a nozzle for fluid distribution in accordance with my design.

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top plan view; and,

FIG. 7 is a bottom plan view.

The broken line showing of interior in the FIG. 6 view is included for the purpose of illustrating and forms no part of the claimed design.
